UNITED STATES PATENT OFFICE

GEORGE W. WATTS, OF WHITING, INDIANA, ASSIGNOR TO STANDARD OIL COMPANY,
OF CHICAGO, ILLINOIS, A CORPORATION OF INDIANA

STEAM LIFT

Application filed July 23, 1925. Serial No. 45,618.

This invention relates to steam lifts and the like and more particularly to a steam lift for use in connection with stills in the treatment of crude oil and its products. The invention is fully described in the following specification and is shown in the accompanying drawings, in which:

Figure 1 is a diagrammatic view showing the steam lift in relation to a still;

Fig. 2 is an enlarged vertical section 10 through the steam lift; and

Fig. 3 is a horizontal section on the line 3—3 of Fig. 2.

In the embodiment illustrated, the steam lift 10 is shown in connection with two stills 11 and 12, the steam lift being located well below the level of oil in the still 11 and connected thereto by means of a downwardly disposed pipe 13. A vertical pipe 14 leads from the steam lift 10 to a column 15 which is here shown disposed above the still 12 and is connected thereto by means of a pipe 16.

The steam lift as illustrated in Figs. 2 and 3 is preferably made of a casting having a 25 converging diverging tube of the Venturi type therein, the tube in the form illustrated having its diverging portion 17 disposed vertically and its converging portion 18 curved. The ends of the tube are flanged as at 19 and 30 20 for convenience of attachment to the pipes 13 and 14. The steam lift is supported by a foot 21.

A circular flange 22 is formed on the lower portion of the body and is adapted to receive a housing 23 which surrounds the neck and diverging portion of the Venturi tube, said housing being preferably welded to the flanges 20 and 22. Steam is introduced into the annular space between the upper portion 40 of the Venturi tube 17 and the housing 23 by means of a pipe 24 which leads to any suitable source of steam supply. A series of apertures (preferably inclined), forming steam jets or nozzles 25 is formed in the upper portion of the Venturi tube 17 and these nozzles preferably project inwardly and upwardly from all sides so that the kinetic energy of the steam entering at high velocity is imparted to the mixture of oil and steam.

It will be understood from the foregoing

that with the still 11 and the pipes 13 and 14 filled with oil which is heated well above the boiling point of water, the introduction of steam into the upper portion of the Venturi tube 17 will form a mixture of steam oil vapor, and hot oil in the tube 14 whose specific gravity is so much lower than that of the heavier oil in the still 11 and in the down-pipe 13 that it will cause the lighter mixture in the pipe 14 to flow up to the column 15 and thence down into the still. At the same time the oil being above the boiling point of water will keep the steam thus introduced in the vapor phase. In the column 15 the steam and the oil vapors carried by it are separated from the unvaporized oil, which descends the column in countercurrent to the steam and oil vapors from the still (11 or 12) to which the column is attached.

The lower portion 18 of the venturi is so proportioned as to impart a uniform acceleration to the oil and the velocity attained at the throat is maintained substantially constant in the upper portion 17 due to its diverging form and to the injection of steam from the jet 25.

In the operation of the device there is a substantial drop in static pressure of the oil or other liquid passing through the tube beyond its neck and in the diverging portion 17. The supply of steam in this portion makes possible the use of steam (or other gas) at a lower static pressure than that of the oil or liquid entering the tube. Thus the oil entering the tube may be at a pressure of, say, 10 pounds per square inch, but its pressure may be so reduced in the diverging portion 17 of the tube that steam or gas may be supplied there at a substantially lower pressure; say, 7 to 8 pounds per square inch.

While I have shown and described but a single embodiment of this invention, it is to be understood that it is capable of many modifications. Changes therefore in the construction and arrangement may be made which do not depart from the spirit and scope of the invention as disclosed in the appended claim.

I claim:

1. In combination, an oil still, a pipe leading

therefrom from below the level of oil therein, said pipe extending downwardly and upwardly to substantially above the level of oil in said still, and a steam lift between 5 said downwardly and upwardly extending portions whereby steam may be injected into the hot oil to vaporize a portion thereof and to cause it to flow from said still, said steam lift comprising a Venturi tube in the lower 10 section of the upwardly directed portion of said pipe and means for causing the steam to be supplied into the diverging portion of said Venturi tube.

In testimony whereof I have hereunto set 15 my hand this 30th day of June, 1925.

GEORGE W. WATTS.
